(57) **CLAIM**

The ornamental design for a selfie stick, as shown and described.

DESCRIPTION

FIG. 1 is a front elevational view of a selfie stick showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, bottom and right perspective view thereof;

FIG. 8 is a front, top and right perspective view thereof; and,

FIG. 9 is an enlarged view of portion 9 of FIG. 7.

The broken lines in the drawings illustrate portions of the selfie stick that form no part of the claimed design.
